Primary Examiner — Shawn T Gingrich*Assistant Examiner* — Katherine E Morris(74) *Attorney, Agent, or Firm* — Plager Schack LLP; Mark H. Plager(57) **CLAIM**

An ornamental design for a folding learning tower, as shown and described.

DESCRIPTION

FIG. 1 is a front perspective view of the learning tower in an open position.

FIG. 2 is a front perspective view of the learning tower in a closed position.

FIG. 3 is a front view of the learning tower.

FIG. 4 is a rear view of the learning tower.

FIG. 5 is a left side view of the learning tower.

FIG. 6 is a right side view of the learning tower.

FIG. 7 is a top view of the learning tower; and,

FIG. 8 is a bottom view of the learning tower.

The broken lines illustrate the portions of the learning tower that form no part of the claimed design.

1 Claim, 8 Drawing Sheets(56)
